UNITED STATES PATENT OFFICE.

GUY B. FITZ, OF AUBURN, MAINE, ASSIGNOR TO FITZ-EMPIRE DOUBLE PIVOT LAST COMPANY, OF AUBURN, MAINE, A CORPORATION OF MAINE.

LAST.

Application filed May 15, 1919. Serial No. 297,264.

To all whom it may concern:

Be it known that I, GUY B. FITZ, a citizen of the United States, residing at Auburn, in the county of Androscoggin and State of Maine, have invented certain new and useful Improvements in Lasts, of which the following is a specification.

This invention relates to block lasts, or lasts having a block or part in the upper part of the instep which is movable to release or restore the lasting tension in the waist of the shoe, thereby enabling the last to be removed from or properly inserted in the shoe.

Block lasts are universally used in turning shoe making, especially in the second lasting. It has been found impractical to put a hinge last into a turned shoe, as it crowds the upper ahead of it when being inserted, instead of stretching it laterally, as desired. The main body of a block last can be placed in the turned shoe without undue longitudinal disturbance of the upper, and the insertion of the block will then pull the upper laterally into proper position.

Some sort of connection has been found necessary between the block and main body of the last in order to prevent loss of the block when the last is not in use, and a cord has been almost universally used for that purpose. The use of the cord is attended with difficulty due to the fact that it gets between the block and main body, thus preventing the proper seating of the block, which is a troublesome accident, especially in a high shoe where the last cannot be easily manipulated. The cord is also frequently cut by being caught between the jack and the last cone, and the block is then separated and often lost.

It is an object of the present invention to remedy the above described difficulties, among others, by providing a connection between the block and the main body, which will not be subject to these disadvantages and will at the same time retain the great advantage of the loose cord connection which permits the block to be disposed out of the way when, for example, a high shoe is being manipulated on a jack, as will be more fully pointed out below.

An important feature of the invention consists in a link connection be-

tween the body and block of a block last arranged to place the block in an inoperative position substantially above its normal operative position, so that it is held in the front opening of a shoe in connection with which the last is being manipulated without undue interference with the shoe parts.

This and other features of the invention will be better understood from the following description of a preferred embodiment thereof selected for illustrative purposes and shown in the drawing which illustrates a last partly in section.

The body 1 of the last and the block 2 may be formed, as is usual, in one piece in a last lathe, and the block then cut out along a scarf 3 by a band saw. In the secant faces of the two parts are preferably formed vertically registering grooves 4 and 5, respectively. The metallic connecting link 6 is seated in these grooves, with its ends pivoted on pins 7 and 8 seated in the body and block respectively. The pivots 7 and 8 are preferably so situated that the line joining them extends forwardly across the cut 3 and makes a forwardly and downwardly opening acute angle with it, for a purpose that will be described.

A socket 9 in the body communicating with the groove 4 contains a coil spring 10 upon which is seated an anti-friction device in the shape of a ball 11 resting against the rear end of the link 6 which is formed with a lateral projection having a hump 12. The hump is so situated that the hump lies on one side or the other of the ball, according as the block 2 is in one or the other of its two extreme positions. The spring and ball thus hold the block resiliently in either extreme position. The link and projection really constitute a lever actuated by the ball. The acute angle between the cut 3 and the link causes the action of the spring to tend to throw the pivot 8 down closer to the cut when the block is in operative position, and therefore to force the block positively into proper position. The described position of the link also enables it to act very directly as a strut to resist any tendency of the block to crowd upward and backward under the lasting tension. The block may have its forward end deeply curved as at 13 in order to seat it firmly in the body at this point,

thus avoiding the necessity of using the well-known dowel, if desired. A hook hole 14 is provided to afford a convenient means of manipulating the block.

5 The drawing shows in dotted lines the position of the block when separated from the body to permit insertion or removal of the last. The block is displaced in a substantially vertical direction, assuming a position 10 directly above its normal position, and consequently well forward of the jack pin thimble. Thus when the last is inverted on a jack, the displaced block will hang alongside and in front of the jack so that a high 15 shoe can be drawn down over the last without interference between the upper and the block. The block will preferably be rotated slightly in being drawn up, so that the lower end will slip back to get better 20 clearance before being raised, and vice versa. The arrangement of the bonding means between the block and body of the last so as definitely to position the block in the front 25 opening of the upper is an important feature of the invention.

Having described my invention, what I claim as new and desire to secure by Letters Patent of the United States is:—

1. A block last having registering grooves 30 in the body and block and a link lying in the grooves and pivoted to the two said last parts, the length of the link being arranged to seat the block properly in operative position and to support it, when displaced, in 35 a position substantially above its operative instep position, well forward of the heel,

whereby the block will be positioned in the front opening of a shoe in connection with which the last is being manipulated.

2. A two-part block last having registering 40 plane vertical grooves in the body and block and a flat link fitting in the grooves and pivoted to the body and block, the length of the link being arranged to seat the block properly in operative position on the body, 45 and the flat contour of the link causing the block to have a substantially vertical movement of displacement, whereby it is kept in front of the last in the front opening of a shoe in which the last is being inserted. 50

3. A block last having a link uniting its body and block, the said link being joined to said parts at its ends respectively, and arranged to present a downwardly and forwardly opening acute angle with the cut in 55 the last when operatively arranged whereby the link tends to crowd the block into operative position when the block is moved toward such position.

4. A block last having a lever uniting its 60 body and block, said lever being pivoted in each part, and means for operating the lever to move the block into operative position.

5. A block last having a lever uniting its body and block, said lever being pivoted in 65 each part, and a resilient member arranged to press on one side or the other of said lever according as the block is in operative or inoperative position to resiliently hold the block in such position. 70

In testimony whereof I affix my signature.
GUY B. FITZ.
